UNITED STATES PATENT OFFICE.

MARSHALL STONEHOUSE, OF SOUTH STOCKTON-ON-TEES, COUNTY OF YORK,
ENGLAND.

KNUCKLE-JOINT ACTION FOR PRESSES, &c.

SPECIFICATION forming part of Letters Patent No. 238,983, dated March 15, 1881.

Application filed October 25, 1880. (Model.) Patented in England April 27, 1880.

To all whom it may concern:

Be it known that I, MARSHALL STONEHOUSE, of South Stockton-on-Tees, in the county of York, England, have invented new and useful Improvements in Knuckle-Joint Actions for Presses and other Pressing or Forcing Apparatus, (for which I have obtained a patent in Great Britain on the 27th day of April, 1880, No. 1,723,) of which the following is a specification.

The object of this invention is to obviate the disadvantages inherent in knuckle-joint or toggle actions as heretofore usually made, and to give the platen or follower, or other equivalent part of a press or other pressing or forcing apparatus, any required length of travel with a force or pressure as near as may be equal throughout. I give the knuckle-joint arms reciprocating motion by any suitable means, and combine the said arms with the stationary head, with a sliding head, and with the platen or follower, the latter being connected to a pressing-screw having nuts which are caused to revolve; or there may be more than one sliding head or more than one screw.

In the drawings, Figure 1 is a front elevation of my improved press, partly in section. Fig. 2 is a side elevation of the same. Fig. 3 is a sectional plan, showing the eccentrics, shafts, and driving-wheels. Fig. 4 is a sectional plan, showing the screw-shaft and sliding head. Fig. 5 is a sectional plan, and Fig. 6 an elevation, of an arrangement by means of which both toggle-arms can be operated from one shaft. Fig. 7 is a front elevation, and Fig. 8 a plan, partially in section, of a modified form of this press, in which gearing is used for communicating power and motion to the parts. Fig. 9 is an elevation, and Fig. 10 a plan, partially in section, of a simpler form of press, the actuating-shaft in which can be run slowly and powerfully when applying the pressure in the press, or more rapidly in returning the parts to their normal position.

The shaft *p* is caused to revolve by belt on the pulley *q*, and has a right-hand worm, *o*, and a left-hand worm, *o'*, which impart slower revolving motion to the worm-wheels *m* and *m'* on the shafts *l* and *l'*, respectively. These latter have eccentrics *k*, which work in blocks

k', whereon the connecting pieces *k*³ are free to slide. To the latter are jointed the toggle-arms *a* and *a'*. The upper ends of the arms *a* and *a'* are jointed to the stationary press-head *H*, and the lower ends to the sliding head *e* and to the sliding head *e'*, and both these heads are bored to fit easily on the external part of the thread of the pressing-screw *d*, which also passes freely through the head *H*, which acts as a guide, but at the same time is prevented from turning therein by a gib, *e*², which projects into a slot formed into said screw *d*, leaving the latter free to move up or down; and *v* is the platen or follower on the bottom end of the screw *d*.

Underneath the sliding heads *e* and *e'* there are two nuts, *b* and *b'*, working on the screw *d*. These nuts are formed as tooth-wheels, as shown, and are caused to revolve intermittently and alternately by means of the tooth-sectors *b*² *b*³, or pinions having teeth on only part of their circumference, as shown clearly in Fig. 4, and they are somewhat deeper than the nut-wheels *b* and *b'*. These are mounted on the vertical spindle *b*⁴, which is revolved by chain, strap, or pulley gear either in one direction or the other, right-round or left-round, from the shaft *l* or the shaft *l'*, which latter revolve continuously in opposite directions, as shown by the arrows, Fig. 1.

g is a clutch sliding on a feather on the shaft *b*⁴, and, by means of the lever *s*, capable of being thrown into gear with the loose chain-pulley *f'* or *t*. The pulley *f'* is driven at a quick speed from the pulley *f*² on the shaft *l'*, the driving-chain passing also over the guide-pulley *x* on the spindle *b*⁴ and the guide-pulley *x'* on the spindle *l'*. The pulley *t* is driven at a slow speed from the pulley *f* on shaft *l*, as shown in plan view, Fig. 3.

To insure a regular and reliable motion of the sliding heads *e* and *e'* and corresponding action or gearing of the sector-pinions *b*² *b*³ with the right teeth or the same teeth of their nut-wheels *b* and *b'* at each revolution of the shaft *b*⁴, it is necessary for this purpose that each nut *b'* and *b* have a star-wheel, *y*, and each sector-pinion *b*² *b*³ a corresponding cam, *z*, gearing therewith, as shown in Fig. 4.

The driving-shaft *p* being caused to revolve,

the shafts l and l' are driven in opposite directions by the worms o and o' and worm-wheels m and m' . The reciprocating motion imparted by the eccentrics k to the blocks k' and connecting-pieces k^3 causes the toggle-arms a a' to bend and straighten alternately, and so move the screw d and platen v downward. The clutch g , by a lever shown in dotted lines, Fig. 1, is thrown into gear with the chain-pulley t , causing the shaft b^4 to turn round from right to left. The tooth sector-pinions b^2 b^3 will each in its turn impart part of a left-to-right revolution to the nuts b and b' , respectively, the cams z and star-wheels y retaining them securely in that position until they are again moved by the toothed sectors b^2 and b^3 . The nut-wheels, being revolved from the left to the right, will thus rise, while the sliding heads e and e' are raised alternately by the bending 15 toggle-arms a a' . The screw d and follower v , not being able to turn, will remain stationary until, on the downstroke caused by the straightening toggle-arms, said screw d will be forced down with the sliding heads e e' and 20 through the stationary head H , and so the movements are repeated alternately. When the platen v has traveled the required stroke, (which may be any desired length,) the clutch g is thrown out of gear with the pulley t automatically or by hand. The platen v may now be brought up quickly by throwing the clutch g in gear with the pulley f' , whereby the nut-wheels b b' are revolved in the opposite direction, causing the platen v to rise with 25 the screw d .

v is the receptacle into which the material to be compressed is placed.

The arms a a' may, if desired, be worked from one shaft having three eccentrics, and on 40 the shaft l are formed said eccentrics. The outside ones, k' k , work the arms a on the left-hand side, and the center eccentric, k^2 , works the arms a on the right-hand side, as shown in Figs. 5 and 6, the other parts of the press 45 being constructed and operating the same as described, and shown by Figs. 1 to 4, inclusive.

Figs. 7 and 8 show a press in which the spindle b^4 is caused to revolve by means of bevel-gear with a slow motion and a quick motion.

50 On the shaft p' of the slow-motion strap-pulley q' are right and left hand worms or screws o o' , gearing into worm-wheels m m' on the shafts l l' , for working the eccentrics. On the shaft l' there is a miter-wheel, f^2 , which gears 55 with a miter-wheel, f^3 , and on the spindle of the latter there is a miter-wheel, f , which gears with a miter-wheel, f' , on the vertical spindle b^4 , communicating the slow descending motion to the screw d and platen v by means of the 60 tooth sector-wheels b^2 and b^3 on the spindle b^4 , said sector-wheels alternately communicating a partial revolving motion to the nut-wheels b and b' on the screw d , causing the latter to descend slowly in the same way as described 65 with reference to Figs. 1 to 4, only that in this case I employ one sliding head e only, instead of two, the nut-wheels b working against the

stationary head H and the nut-wheel b' against the sliding head e .

g is the pulley for the quick-motion shaft p , 70 which is brought into action by suitable means when the quick down or up motion is required for the screw d and follower v .

On the shaft p there is a sliding clutch, g , for bringing the shaft p in fixed connection 75 with the miter-wheel r or the miter-wheel r' , thereby causing the eccentric-shaft l to revolve in one direction or the other, for lowering or raising the screw d rapidly, and, by the spur-wheels t t' t^2 t^3 , to communicate motion to the 80 other eccentric-shaft, l' , which acts on the spindle b^4 . The shafts l and l' have clutches M and M' , for putting in gear the worm-wheel m and m' , according as required in working the press by a slow or a quick motion through the quick- 85 motion pulley q' or the slow-motion pulley q . By the above arrangement it will be seen that the screw d may be given varied speed for the downstroke or upstroke.

A plan of a much simpler arrangement of 90 press is shown in Figs. 9 and 10, in which the speed is uniform throughout the upstroke and the downstroke of the screw d , but where, by the driving-strap-pulley arrangement outside of the press itself, the screw d may nevertheless receive uniformly slow descent and uniformly quick ascent; or, if desired, by means of cone-pulleys outside of the press itself, the screw d may receive a gradually-decreasing speed in the descent and a gradually-increasing speed in the ascent. The worm-shaft p is in this case provided with fast and loose belt-pulleys at each end, one belt being open and the other crossed, so that it may receive a right-hand or left-hand revolving motion—one 95 for the ascent and the other for the descent of the screw d . The worms o and o' , gearing with the worm-wheels m and m' , cause the eccentric-shafts l and l' to revolve as before. The vertical spindle b^4 receives motion from 100 the shaft l by means of the miter-wheels f f' f^2 f^3 . It will thus be seen that the miter-wheels r r' , (shown in Figs. 7 and 8,) and also the spur-wheels t t' t^2 t^3 and clutches M M' , are omitted. 105

The arms may be connected directly to the platen and the gearing be between the upper ends of arms and the head-block.

The press may obviously be arranged vertically inverted or horizontal.

For obtaining a quick ascent or descent I may, by suitable gear, cause the barrel d to revolve and so screw it up through the nut-wheels b' and b^2 .

I claim as my invention—

1. The toggle-arms a a' , stationary head H , and sliding heads e e' , in combination with the alternately-revolved nut-wheels b b' , pressing-screw d , and platen v , to which heads and nut-wheels alternate step-by-step motions are 130 communicated, substantially as described.

2. The toggle-arms a a' , sliding heads e e' , and nut-wheels b b' , in combination with the motive spindle b^4 , toothed sector-wheels b^2 b^3 ,

cams z , and star-wheels y , said parts communicating an alternate step-by-step and descending or ascending motion to the screw d and platen v , substantially as described.

5 3. The toggle-arms a , in combination with the stationary head H and sliding head e , and the alternately - revolved nut - wheels b b' , screwed cams z , and gearing, substantially as described.

10 4. In combination with a pressing-screw, d ,

and the two nut-wheels b b' thereof, toggle-arms a a' , a follower mechanism for actuating the toggle-arms, and means for turning the nut-wheels b b' alternately when the strain is relieved from such nut-wheels, substantially as 15 specified.

MARSHALL STONEHOUSE.
